UNITED STATES PATENT OFFICE.

WILLIAM THOMAS REDMAN, OF BRENTWOOD, MARYLAND.

METHOD AND MEANS FOR CONSTRUCTING HOLLOW-CONCRETE WALLS.

Application filed January 21, 1927. Serial No. 162,525.

This invention relates to structures of concrete and like material which are adapted to be poured, or tamped into suitable forms which are removed, after the material has set, to be readjusted for continued use in the same or subsequent work.

The present invention contemplates means for forming hollow blocks and comprises core members and plate members, the spaces 10 formed between the core and plate members, when properly set up, constituting the mold into which the concrete or other material is poured to form the block.

In accordance with the invention the plate member corresponding with the face of the block or structure is finished, or ornamented, to harmonize with the design of the block and is preferably arranged in horizontal position and a layer of the material is spread 20 thereon and a reinforcement applied thereto. This plate thus prepared is placed in position and the mold space filled with the material forming the body of the block. The facing material, usually of sand and cement, spread 25 upon the plate assures a close textured surface which could not be attained by filling the mold with the usual mixture of sand, gravel and cement and omitting the preparatory step of applying the facing material to the outer 30 forming plate.

While the drawings illustrate a preferred embodiment of the invention, it is to be understood that in adapting the means to meet specific needs and requirements the design 35 may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a perspective view of a form, 45 or mold, embodying the invention, showing portions of a concrete structure resulting from the use thereof.

Figure 2 is an enlarged transverse sectional view on the line 2—2 of Figure 1.

Figure 3 is a side view of two core members in the position which they occupy when placed between the plate members, the plate member on the near side being omitted.

Figure 4 is a detail perspective view of the 55 facing plate member having a layer of facing material applied to a portion thereof and a

metal reinforcement applied to the facing layer.

Corresponding and like parts are referred to in the following description and designated 60 in the several views of the drawings by like reference characters.

The numeral 1 designates a hollow concrete structure and 2 is the space formed therein, the spaced walls being connected by 65 ties 3. The numeral 4 designates the facing which consists solely of sand and cement so as to present a close texture, free from spaces and air holes. The body of the structure consists of a mixture of sand, gravel and cement 70 in determinate proportions.

The mold comprises core members for forming the spaces 2 and plate members corresponding to the inner and the outer walls of the structure. The mold may be of any 75 determinate length and usually comprises sections of standard length to admit of adapting the form to varying lengths and courses in the formation of the structure. The numerals 5 and 6 designate the plate members 80 comprising the mold or form and these members are of uniform length and width, and may consist of metal, wood, or other suitable material. The inner plate member 5 has its forming surface roughened, or finished in any 85 preferred way, and as shown, a wire fabric 7 is applied thereto, the purpose being to give a rough surface to the inner face of the walls to insure a keying of the plaster or other finishing coat applied thereto. The forming 90 face of the outer plate member 6 may be ornamented or finished according to any design to be imparted to the outer surface of the wall or structure. The plate members 5 and 6, when properly set up, are spaced apart 95 a distance corresponding to the thickness of the wall or block to be constructed. Tie rods 8 connect the plate members 5 and 6. To prevent spreading of the plate members 5 and 6 and to insure correct positioning thereof 100 metal strips 9 are provided and longitudinal edge portions are bent in opposite directions from the intermediate portion and at a right angle thereto, as indicated at 10 and 11. The flanges 11 thus formed are secured 105 to opposite sides of the wall by suitable means, such as rods 8^a which replace the tie rods 8 previously molded therein. The flanges 10 extend along the outer side of the members 5 and 6 and are secured thereto by the tie 110 rods 8 confining said members in position. In this manner alinement of the mold is as-

sured and displacement thereof prevented. These reinforcing and confining strips 9 prevent any possible buckling or warping of the plate members.

5 The core members are disposed between the plate members 5 and 6 and each consists of similar side plates 12 of a width equal to the width of the plate members 5 and 6 to admit of the upper and the lower edges of the several plates terminating in corresponding planes. End pieces 13 are disposed between the ends of the plates 12 and these end pieces taper throughout their length and are disposed with their larger ends facing downwardly. The ends of the plates 12 are oppositely inclined and the core members are arranged to provide spaces between adjacent ends to correspond with the wedge shaped ties 3 forming connecting means between the 10 walls of the structure bordering upon the space 2. Fillers 14 are provided to be interposed between the plate members 5 and 6 and the core members to prevent inward movement of the plate members when the 15 form or mold is set up preliminary to supplying of the material thereto. The several elements 13 and 14 are clamped between the outer plate members and the core members. The end pieces 13 are of a length to project 20 a short distance below the side plates 12 so as to enter the space 2 of the block or wall previously formed. After the mold space has been partly filled the spacing elements 14 are 25 removed, it being remembered that the lateral pressure of the material is sufficient to retain the several parts in place. After the spacers 14 have been removed the mold is 30 completely filled to the upper edges of the plates 5, 6 and 12. After the material has 35 set the nuts applied to the threaded ends of the tie rods 8 are removed, thereby admitting 40 of removal of the plate members 5 and 6. The wedge elements 13 are driven downwardly 45 a distance to release the plates 12 which are then removed, after which the end pieces 13 are likewise withdrawn and the mold reassembled for a repetition of the operation.

50 Preliminary to assembling of the mold, the facing plate member 6 is arranged substantially in horizontal position and a layer of the facing material is applied thereto, as indicated at 4, the same being spread by means of a trowel to the required thickness. A wire fabric 15 is placed upon the layer 55 4 of the facing material and is embedded therein and serves to retain such layer in place, and also constitutes a reinforcement for strengthening the wall, block or like structure. The facing plate member thus 60 prepared is placed in position to complete the mold or form, and is held in place by means of the tie rods 8 and properly spaced by means of the fillers 14. The material forming the body of the block or structure 65 and usually consisting of sand, gravel and

cement, is poured, or otherwise supplied to the mold space in substantially the manner herein indicated. It is observed that the several elements comprising the mold members may be advantageously formed of concrete 70 which is reinforced in any suitable manner and may, if desired, be faced with sheet metal. The wall is formed in courses, each course being permitted to set before removing the mold therefrom. The lower ends of the elements 13 are reduced slightly to facilitate their entrance and removal from the upper ends of the spaces 2. A plate 16 projects laterally from the lower end of each of the elements 13 and is equal in width thereto to 75 come between the inner faces of the walls bordering upon the space 2. These plates 16 come together and support the concrete forming the bond or tie 3. When the mold is placed upon the wall previously formed 80 the plates 12 rest upon the wall adjacent the space 2 and the plates 5 and 6 rest upon the strips 9. See Figure 2 of the drawings. The mold is positioned so that the bonds or ties 3 will not interfere with the lower ends 85 of the elements 13 and prevent their entrance into the space 2. The space between the plates 12 and the plates 5 and 6 is closed by the wall as shown most clearly in Figure 2. The bond or tie forming space is closed at 90 its bottom by the plates 16, as indicated most clearly in Figure 3 of the drawings.

Having thus described the invention, I claim:

1. A mold for forming a hollow block or 100 structure of concrete, the same comprising outer plate members, core members arranged between the plate members and having their adjacent ends spaced apart, ties connecting the outer plate members and fillers interposed 105 between the plate members and core members.

2. A mold for forming concrete blocks, or 110 structures, the same comprising outer plate members, metal strips having longitudinal edge portions bent to form flanges which extend in opposite directions, corresponding flanges engaging opposite sides of the block, or like structure, and the other flanges engaging outer sides of the plate members, and tie rods connecting the plate members and 115 engaging the flanges of the metal strips in contact with the outer sides thereof.

3. A mold for forming a hollow block or 120 structure of concrete, the same comprising outer plate members, inner core members having adjacent ends spaced apart and comprising side plates and wedge shaped end pieces, tapering spacers between the said plate members and the core members, and tie rods connecting the outer plate members and 125 clamping the core members and spacers between the said outer plate members.

In testimony whereof I affix my signature.
WILLIAM THOMAS REDMAN. [L. S.]
